WELDING ELECTRODE HOLDER

Oscar W. Myers, United States Navy

Application September 1, 1936, Serial No. 98,870

1 Claim. (Cl. 219—8)

(Granted under the act of March 3, 1883, as
amended April 30, 1928; 370 O. G. 757)

This invention relates to an electrode holder, and has for an object to provide an improved electrode holder particularly adapted for holding an electrode used for arc welding purposes, where-
5 in the electrode may be rotated to any desired degree and held at any desired angle, but where the gripping holder and the cable remain sta-
tionary, that is, non-rotating.

A further object of this invention is to provide
10 an electrode holder wherein the electrode is held in uniform tension provided by a spring, yet wherein the electrode may be easily released therefrom when desired with a minimum of effort.

A still further object of this invention is to
15 provide an electrode holder made up of a number of easily assembled parts, light in weight, convenient to operate, and capable of carrying high amperage for the electrode without itself becoming too hot to handle.

20 With the foregoing and other objects in view, the invention consists in the construction, combination and arrangement of parts, as will be described more fully hereafter.

In the drawing:

25 Fig. 1 is an elevational view of the electrode holder in completely assembled position;

Fig. 2 is a top plan view of Fig. 1, the releasing lever and spring being omitted.

The electrode holder shown at 10 comprises a
30 plunger bar 11 having an electric cable 12, suit-
ably secured thereto in any convenient manner
within the insulating handle 13. It will be ob-
served that the plunger bar 11 is of substantially
35 the same diameter as the cable 12, and will be of
a suitable material such as copper or the like, so
that it can carry the full amperage carried by
the cable 12 with substantially no heating effect
whatever.

Extending upwardly from the plunger bar 11
40 are a pair of arms 14 which are apertured at
their upper end so as to provide a journal for the
releasing lever 15, which may be pivoted through
the aperture in the arms by means of a bolt 16.
Releasing lever 15 is in the form of a bell crank
45 lever and has bifurcated arms 17 at one end pro-
vided with oblong slots 18, the other arm 19
resting against a compression spring 20, the
other end of the compression spring 20 being set
50 in the recess 21 within the handle 13. As will be
apparent, the compression spring 20 tends to pivot
the releasing lever 15 about the pivot 16 and away
from the handle.

A hollow sleeve 22, having an outturned flange
55 23 at one end thereof, is provided with a pair of
links 24 ending in enlarged knobs 25 which ex-

tend into the oblong apertures 18 in arms 17 so
as to cause the longitudinal movement of the
sleeve 22 to be controlled by the lever 15. A sec-
ond sleeve 26 is swivelly connected to the sleeve
22 as by having a bell 27 integrally formed at one
5 end thereof, adapted to engage over the flange 23
of sleeve 22. A plurality of fingers 28 are provid-
ed on the bell 27 and are adapted to be folded
over the flange 23 of sleeve 22 so that the sleeve
26 will partake of the longitudinal movement of 10
the sleeve 22, but will be free to rotate relative
thereto.

The sleeve 26 is of such length that it just ex-
tends beyond the end 30 of the plunger bar 11.
This end of the sleeve 26 is provided with a pair 15
of aligned apertures 29 through which the elec-
trode may be inserted. The electrode may be in-
serted through both the apertures 29, in which
case it will extend at right angles to the direction
of the plunger 11, and will be held tightly be-
20 tween the end 30 of the plunger 11 and the sides
of the apertures 29 by reason of the compression
spring 20 urging the bell crank lever 15 in an
anticlockwise direction, thus drawing the sleeve
26 in the direction of the handle 13. Instead of 25
placing the electrode through both apertures 29
it may be inserted through one of the apertures
29 and out through the end of the hollow sleeve
26, in which case it will be held at a 45° angle to
the plunger 11. In either case, the sleeve 26 30
with the electrode may be freely swivelled about
the plunger 11, while the plunger 11 and handle
13 are held stationary, that is, non-rotative, there-
by enabling the electrode to be held conveniently
35 at any angle suitable to the work being per-
formed. When the electrode is substantially used
up and it is necessary to replace the same, it is
released by merely pressing the arm 19 of bell
crank lever 15 against the compression spring
40 20, and a new electrode may be substituted.

Other modifications and changes in the propor-
tions and arrangements of the parts may be made
by those skilled in the art without departing from
the nature and scope of the invention, as defined
in the appended claim.

45 The invention described herein may be manu-
factured and used by or for the Government of
the United States of America for governmental
purposes without the payment of any royalties
thereon or therefor.

50 Having thus set forth and disclosed the nature
of this invention, what is claimed is:

An electrode holder comprising a plunger bar,
an electric cable connected to one end of said
plunger bar, a handle encompassing the con-

nection between said plunger bar and said electric cable, a sleeve mounted for sliding movement on said plunger bar, link means extending from the end of said sleeve nearer said handle, a bell crank lever, mounting means on said plunger bar on which said bell crank lever is journalled, said link means being connected to one arm of said bell crank lever, a compression spring between the other end of said bell crank lever and said handle, 5 a second sleeve rotatably secured to the further 10

end of said first mentioned sleeve, the unsecured end of said second sleeve having apertures therethrough, said apertures being adapted to receive an electrode therethrough, said spring normally urging said bell crank lever to draw said sleeves onto said plunger bar to thereby hold an electrode extending through the apertures in the second sleeve against the end of the plunger bar. 5
